UNITED STATES PATENT OFFICE

JOHN G. H. LIEBEL AND EDWIN S. FLARSHEIM, OF CINCINNATI, OHIO, ASSIGNORS TO THE LIEBEL-FLARSHEIM COMPANY, OF CINCINNATI, OHIO, A CORPORATION OF OHIO

SPARK-GAP MECHANISM

Application filed July 13, 1928. Serial No. 292,509.

This invention relates to spark gap mechanisms of the type particularly adapted for use in high frequency electro-therapeutic apparatus.

5 In spark gap mechanisms of this type it is desirable to have a plurality of individual gaps connected in series, each gap set relatively closely rather than the single gap having its electrodes set a large distance apart. 10 It is further desirable to have the individual gaps of the series set relatively uniformly, and it has therefore been found expedient to mount a plurality of spark electrodes upon a stationary member and a plurality of opposing electrodes upon a member movable relatively to the support for the first set of electrodes. In this way the series 15 of gaps is unitarily adjustable; access to the gaps is easily had and cleaning can be readily accomplished.

The object of the invention is to provide simple and convenient spark gap mechanism adapted in the proper environment to produce a smooth and steady high frequency current.

25 This invention is predicated upon the determination that unexpected efficiency is attained by shielding the gaps from one another by members opaque to ultra-violet radiation. Ultra-violet radiation has an ionizing effect upon the atmosphere which tends to break down a spark gap unduly quickly with the result that the proper and due power is not delivered by the instrument of which the spark gap mechanism is a part.

30 Shields are therefore disposed between the individual gaps, thereby cutting down the radiation of ultra-violet from one to another which greatly increases the power of the instrument and the efficiency of the spark gap mechanism.

35 This invention therefore comprises a series of spark gaps disposed in substantially the same plane, and a plurality of shields between said gaps to inhibit ultra-violet radiation from one to another.

40 A preferred embodiment of this invention is illustrated in the accompanying drawings which disclose the spark electrodes and associated radiator plates mounted for facile adjustment and cleaning yet protected from one

another's influence by appropriately disposed shields.

Figure 1 is a front view of the improved spark gap.

Figure 2 is an end view thereof.

Figure 3 is a sectional view taken on line 3-3, Figure 1, detailing the adjustment mechanism.

Figure 4 is a sectional view taken on line 4-4, Figure 1, showing the mounting of a set of electrodes.

Figure 5 is a sectional view taken on line 5-5, Figure 4, further detailing the mounting of the electrodes.

Figure 6 is a view illustrating the shield for cutting down the radiation of the ultra-violet rays from one to another of the gaps.

Figure 7 is a sectional view taken on line 7-7, Figure 6, further detailing the arrangement of the shield.

70 The spark gap comprises a base 1 which has two side standards 2 and 3 secured to it by L members 4 attached to the base member 1 by means of screws 5 and to the side standards by means of screws 6 and nuts 7. 75 These side standards are placed opposite to each other so that the gap bars may be mounted between them.

76 A stationary bar 8, made of glass or some other insulating material, is mounted between these side standards 2 and 3 by means of two brackets 9, one of which extends inwardly from each side standard, and clamping rings 10 which surround the bar at its ends and are secured to said brackets by nuts 11 disposed on screws 12 which pass through the ends of the clamping rings and the brackets.

80 The movable gap bar 13 is placed below the stationary gap bar as disclosed, and is provided with rings 14 at its ends which are secured to brackets 15 by means of nuts 16 disposed on screws 17 which pass through the ends of the rings and the bracket. Between brackets 9 and 15 extend coiled springs 18 secured at their ends through eyelets disposed 85 in the ends of screws 12 and pins 19 which extend through the brackets 15.

86 The brackets 15 are secured to slide bars 20 toward their middles, the lower ends of these slide bars being slotted, said slots having en- 100

gagement with pins 21 extending outwardly from the side standards 2 and 3. The upper ends of these slide bars are pivoted into engagement with the ends of a yoke 22, each arm of which is pivoted to a side standard. 5 The yoke comprises the two arms pivoted to the side standards and a member 23 joining them some distance in back of the side standards. At the end of this member 23 is pivoted a nut 24 into which is screwed one end of an adjustment screw 25. This adjustment screw 25 is provided with a knurled end 26 and a shoulder 27 bearing downwardly against a horizontal flange 28^a as a part of a 10 standard 28 attached to the base. Consequently, rotation of this adjustment screw swings the yoke, moves the slide bars and varies the space between the stationary and movable gap bars. The raising of this adjustment screw 25 upwardly axially tends to 15 separate the gap bars rapidly against the tension of coiled springs 18 and facilitates the cleaning of the mechanism.

Toward one another from both the stationary and movable gap bars extend a plurality 25 of radiator plates 29, adapted to support the spark electrodes 30 themselves. As disclosed, the radiator plates are grouped in sets of four plates disposed parallel to each other 30 and spaced slightly. The plates are secured together in this spaced relationship by posts 31 and collars 32 placed on said posts between plates. On the outer ends of the posts are disposed the spark electrodes. Each set 35 of radiator plates is held to its supporting gap bar by means of a ring 33 disposed about the bar and screwed, welded or otherwise secured to the back plate of the set.

As disclosed, the stationary gap bar is provided with five sets of radiator plates, said sets slightly spaced from each other horizontally, each set provided with two spark electrodes, one at each side of the forward radiator plate, all of said spark electrodes substantially in alignment with each other. 40

The movable gap bar, as disclosed, is provided with four sets of radiator plates similar to those carried by the stationary gap bar. These sets are disposed in staggered relationship to the sets carried by the stationary gap bar so that the spark electrodes carried by any given set of radiator plates are disposed opposite to the spark electrodes of two different sets carried by the opposite gap bar. 45

The movable gap bar is also provided with two sets of small radiator plates 34 disposed adjacent to the ends of the gap bar. These sets also carry spark electrodes placed opposite to the end spark electrodes carried by the sets of plates supported by the stationary gap bar. This structure provides a series of 50 ten spark gaps disposed in substantially the same plane.

Each set of radiator plates (except the 55 sets 34) carries a shield 35 which extends

toward the opposing gap bar. Each shield is disposed intermediate the two spark electrodes carried by the plate so as to shield each gap from the radiation of the adjacent gaps. As disclosed, these shields are 70 secured to the innermost radiator plates by means such as welding, riveting, etc.

Figure 7 discloses shields comprising tubes 36 of glass or other insulating material impervious or opaque to ultra-violet radiation placed over the opposing spark electrodes and thus to inhibit radiation of ultra-violet light from one gap to another. 75

In use the radiator plates 34 are connected into the desired circuit which disposes all 80 ten of said gaps in said circuit in series with one another. The spark gap of this invention is therefore simple in structure, easy to adjust or clean, and adapted to provide out-put current of smooth, steady and high 85 voltage by virtue of the members which insulate the gaps from one another as to ultra-violet radiation.

Having described our invention, we claim:

1. A spark gap mechanism particularly 90 adapted for use in high frequency electro-therapeutic instruments and the like, said mechanism, comprising, a stationary member, a member movable in relation thereto, a plurality of spark electrodes supported by the stationary member, a plurality of opposing spark electrodes supported by the movable member constituting adjustable spark gaps in combination with the spark electrodes on the stationary member, said 95 gaps defined by substantially the same planes and shields disposed between said gaps to inhibit the radiation of ultra-violet light 100 from one to another.

2. A spark gap mechanism particularly 105 adapted for use in high frequency electro-therapeutic instruments and the like, said mechanism, comprising, a stationary member, a member movable in relation thereto, a plurality of radiator plates carried by each 110 of said members, a plurality of spark electrodes attached to said radiator plates and disposed in opposing relationship to each other to constitute a series of spark gaps, and shield members disposed between each 115 of said gaps to inhibit radiation of ultra-violet light from one to another.

3. A spark gap mechanism particularly 120 adapted for use in high frequency electro-therapeutic instruments and the like, said mechanism, comprising, a stationary supporting member and a member movable relatively thereto, a plurality of radiator plates grouped in a series of sets, each set, comprising, a plurality of parallel spaced plates, 125 some of said sets supported by said stationary member, some by said member movable relatively thereto, the sets carried by the stationary member staggered in relation to the sets carried by the movable 130

member, a plurality of spark electrodes carried by said radiator plates, two for each set of plates, said spark electrodes so disposed that the two electrodes of any 5 given set are in opposing relationship to electrodes of two different sets supported by the opposite member, and shields disposed between the gaps formed by said opposing electrodes to prevent ultra-violet radiation 10 from one gap to another.

4. A spark gap mechanism particularly adapted for use in high frequency electro-therapeutic instruments and the like, comprising, a plurality of spark electrodes disposed in opposing pairs to constitute a series 15 of gaps defined by substantially the same planes, a series of radiator plates disposed about said spark electrodes, and members opaque to ultra-violet light supported by 20 said radiator plates and extending therefrom to positions between the gaps to inhibit the radiation from one gap to another.

In witness whereof, we hereunto subscribe our names.

25 JOHN G. H. LIEBEL.
EDWIN S. FLARSHEIM.
